(57) **CLAIM**

The ornamental design for a knife sharpener, as shown and described.

DESCRIPTION

FIG. 1 is a front, right and top perspective view of a knife sharpener showing my new design, wherein the sharpener and base components are shown in a state of use;

FIG. 2 is a front, right and top perspective view of the sharpener component of the knife sharpener;

FIG. 3 is a rear, left and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a front, right and top perspective view of the sharpener component of the knife sharpener, wherein the unclaimed end parts are shown a disassembled state;

FIG. 11 is a front, right and top perspective view of the base component of the knife sharpener;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof; and,

FIG. 18 is a bottom plan view thereof.

The broken lines shown in the drawings illustrate portions of the knife sharpener that form no part of the claimed design.
